SHOE FASTENER

Henry J. Pote, Swampscoot, Mass.

Application October 12, 1933, Serial No. 693,365

4 Claims. (Cl. 24—145)

This invention relates to shoe fasteners and has for an important object thereof the provision of a fastener which is adapted to be mounted upon any conventional type of shoe wherein the front 5 of the shoe is open so as to provide a means whereby the shoe may be drawn into closed position more easily than is possible with the present type of eyelet fasteners.

Another object of this invention is to provide a 10 fastener which is so constructed that all of the lace will be disposed on the outside of the shoe and will, therefore, easily ride over the fastener, thereby permitting the use, in certain types of shoes, of a single lace.

15 A further object of this invention is to provide a fastener of this kind which is relatively simple in construction and can be readily and cheaply manufactured and which will take the place of the present eyelet structure used in shoe constructions.

20 The above and various other objects and advantages of this invention will in part be described and in part be understood from the following detailed description of the present preferred embodiment, the same being illustrated in the accompanying drawing, wherein:—

25 Figure 1 is a fragmentary top plan view of a shoe structure having devices constructed according to the preferred embodiment of this invention mounted thereon;

30 Figure 2 is an enlarged sectional view taken on the line 2—2 of Figure 1;

35 Figure 3 is a fragmentary top plan of a shoe structure having a modified form of fastener mounted thereon;

40 Figure 4 is an enlarged sectional view taken on the line 4—4 of Figure 3;

Figure 5 is a fragmentary sectional view partly in detail of the modified form shown in Figures

45 3 and 4.

Referring to the drawing wherein like characters of reference designate corresponding parts throughout the several views, the letter S designates generally a shoe structure which has an open upper as at 10. In the conventional shoe structures and particularly the shoes of the low type, such as oxfords, the shoe laces are threaded through eyelets or holes punched through the opposite sides of the open portion of the upper 10 50 of the shoe. The mounting of these eyelets in the shoes adds a considerable cost to the manufacturer of the shoe and in addition thereto when the purchaser laces up the shoe, the laces do not readily slide through the holes or eyelets in view 55 of the fact that a portion of the lace is disposed

on the lower surface of the shoe between the foot and the shoe while another portion is on the outside of the shoe.

In order to permit the quick lacing up of a shoe or the drawing of the split portion of the upper together quickly, I have provided, as shown in Figures 1 and 2, a grommet generally designated as 11 which comprises a cylindrical body 12 which is adapted to be disposed in a hole or opening 13 in the shoe portion 10 and to project 60 through this opening. The outer portion of the grommet 11 has an outstanding flange 14 and the inner end of the grommet 11 is adapted to be turned over as at 15 so as to clamp the central portion 12 within the opening 13. A looped member 16 is integral with the grommet 11 and this looped member has a free end 17 extending into the opening of the grommet 11 so that it will not constitute a projection which will have a tendency to cut the shoe lace which is extended through 70 this loop or eye member 16. The other end of the member 16 is integral with the flange 14 and the major portion of the loop or eye 16 overlies the central portion of the grommet 11. When this grommet or fastener 11 is mounted in the shoe, 75 the eyelet or eye 16 is disposed transverse to the length of the split portion of the upper 10 so that the opening will be disposed longitudinally of the shoe.

80 A shoe lace L is adapted to be threaded through the eye 16 and one end of the lace L may be secured to the foremost eye 16 and the other end threaded crosswise of the shoe and through succeeding eyes. The opposite end of the lace L is then pulled so as to draw the split portion of the upper 10 together and this end is then inserted 85 between a fastening member 18 secured as by a rivet 19 to the side of the shoe.

I have shown in Figs. 3 and 4 another form of fastener which may be mounted on a shoe S' and this modified form of fastener comprises a round post designated 20 having a base flange 21 and a head 22. A flanged rivet 23 is adapted to engage the interior of the post 20 and to be extended through an opening 24 in the shoe S'. This rivet 90 23 has a flange 25 which coacts with the flange 21 in holding the post 20 in secured position in the shoe S'.

100 A cap 26 engages over the head 22 and has the lower edge portion 27 thereof at diametrically opposed sides pressed inwardly so as to engage beneath the head 22 and thereby hold the cap tightly on the head 22. A lug 28 is integral with the cap 26 and extends downwardly over the head 22 and engages alongside the post 20 and coacts with 105 110

the crimped opposite side portions 27 of the cap to hold the cap in adjusted position.

A bar 29 extends downwardly from the cap 26 and has an inturned lower end portion 30 engaging over the outer edge of the flange 21 and this bar 29 coacts with the confronting side of the post 20 to form an eye 31 through which the lace L' is adapted to be threaded. The fastener herein described is adapted to be mounted with the eye 31 on the outer side of the shoe S' or, in other words, the eye 31 is positioned on the opposite side of the split portion of the shoe. In this manner, the bar 29 will act only to hold or maintain the lace L' in the eye 31 whereas the post 20 acts as a guide means or a slide over which the lace L' is adapted to be moved. The round surface of the post 20 will permit the lace L' to readily move thereover.

Any desired number of these fasteners may be mounted on the shoe and, as shown in the drawing, this type of fastener permits the mounting of the face on the outside of the shoe without any portion thereof being threaded beneath the shoe as is the case with the conventional eyelets.

The bar 29 coacts with the post 20 to form the loop similar to the loop or eye 16 which is positioned on the outside of the shoe so that no portion of the lace threaded therethrough will be positioned on the inner side of the shoe.

It is, of course, understood that various changes and modifications may be made in the details of construction and design of the above specifically described embodiment of this invention without

departing from the spirit thereof, such changes and modifications being restricted only by the scope of the following claims.

I claim:—

1. A shoe lace fastening means comprising an open loop, and a grommet integral with one end of the loop, said loop being disposed at a right angle to the grommet and having the free end thereof extending interiorly of the grommet diametrically opposite to the connection of the loop with the grommet. 80

2. A shoe lace fastening means comprising a cap, means securing the cap to a shoe structure in offset relation thereto, and means integral with the cap and coacting with the first means to provide an eye perpendicular with the outer surface of the shoe. 85

3. A shoe lace fastening means comprising a cap, a post, means for securing the post to a shoe structure, means for securing the cap to the post, and means integral with the cap and engaging the post to thereby provide an eye on one side of the post and in offset relation to the outer surface of the shoe. 90

4. A shoe lace fastening means comprising a cap, a post, means for securing the post to a shoe structure, a head carried by the post and engaging within the cap, means for securing the cap to the head, and a strap carried by the cap and engaging beneath the post to provide an eye on one side of the post in perpendicular relation to the outside surface of the shoe. 100
